CLAIM

The ornamental design for a clay target stand as shown and described.

DESCRIPTION

FIG. 1 is a perspective view of a clay target stand showing our new design;

FIG. 2 is a front elevational view thereof, a back elevational view thereof being identical thereto;

FIG. 3 is a right-side elevational view thereof, a left-side elevational view thereof being a mirror image of the right-side elevational view;

FIG. 4 is a top plan view thereof; and,

FIG. 5 is a bottom plan view thereof.

Dash-dash broken lines in the figures illustrate portions of the clay target stand that form no part of the claimed design. Dot-dash broken lines in the figures are boundary lines illustrating bounds of the claimed design and form no part of the claimed design.
